UNITED STATES PATENT OFFICE

JAMES L. BROWNELL, OF ST. PETERSBURG, FLORIDA, ASSIGNOR TO CHECKER CAB MANUFACTURING CORPORATION, OF KALAMAZOO, MICHIGAN

DESIGN FOR A VEHICLE WHEEL

Application filed December 30, 1931. Serial No. 42,306. Term of patent 14 years.

To all whom it may concern:

Be it known that I, JAMES L. BROWNELL, a citizen of the United States, residing at St. Petersburg, in the county of Pinellas and State of Florida, have invented a new, original, and ornamental Design for Vehicle Wheels, of which the following is a specification, reference being had to the accompanying drawing, forming part thereof.

Fig. 1 is a perspective view of a vehicle wheel showing my new design, and

Fig. 2 is a side elevation of the body portion thereof.

The salient feature of the design consists in the provision of a disk vehicle wheel of conical shape having a plurality of indenta-

tions in the main body thereof enclosing the respective attaching bolts individually and forming sunken sockets for the reception of the nuts coacting with the bolts within the recesses. These localized recesses do not interfere with the general conical effect of the disk and form a striking design in which the attaching nuts are practically entirely received within the individual sockets. The disk has a central hub plate disposed within the plane of the outer side of the disk.

I claim:

The ornamental design for a vehicle wheel, as shown and described.

JAMES L. BROWNELL.
